UNITED STATES PATENT OFFICE.

JESSE I. HARDY, OF ST. LOUIS, MISSOURI, ASSIGNOR OF ONE-HALF TO PAUL A. GLANVILLE, OF ST. LOUIS, MISSOURI.

FIRE-EXTINGUISHER.

No. 853,451.

Specification of Letters Patent.

Patented May 14, 1907.

Application filed July 20, 1906. Serial No. 327,013.

To all whom it may concern:

Be it known that I, JESSE I. HARDY, a citizen of the United States, and a resident of the city of St. Louis and State of Missouri, have invented a new and useful Improvement 5 in Fire-Extinguishers, of which the following is a specification.

My invention relates to chemical fire extinguishers, and has for its principal objects 10 to avoid the sticking of the plunger; to insure its proper operation; to avoid the lodging of fragments where they would be likely to interfere with the proper operation of the device; to insure the breaking of the acid bottle; and to secure other advantages hereinafter appearing.

My invention consists in the parts and in the arrangements and combinations of parts hereinafter described and claimed.

20 In the accompanying drawings which form part of this specification, and wherein like symbols refer to like parts wherever they occur, Figure 1 shows in vertical section the upper portion of a chemical fire extinguisher embodying my invention; and, Fig. 2 is a detail view showing the plunger in its lowermost position.

My device comprises an ordinary alkali tank 1 having an annular flange 2 on the inner wall of the neck 3. Suspended from 30 this annular flange is a skeleton cage 4 which supports the acid bottle 5. The upper end of the neck is screw-threaded exteriorly and has an interiorly screw-threaded closure cap 35 7 fitted thereon, with a rubber gasket 8 intervening between the end of the neck and the body of the cap.

The closure cap has a tubular projection 9 on its inner face, the upper end of said projection, that is the portion thereof next to the body of the cap, is enlarged, and the shoulder 10 between the portions of different diameters is beveled off exteriorly and finished to constitute a valve seat.

45 The bore of the tubular projection 9 extends through the body of the cap and a boss on the top side thereof. Through this bore extends a stem 11 of a plunger, said stem being arranged to fit and slide freely in the bore. The inner projecting end of the stem is provided with an annular flange or tubular enlargement 12 arranged concentric with the stem and of such internal diameter as to permit it to fit and slide loosely over the

narrower portion of the projection 9. The 55 tubular or annular enlargement 12 is longer than the narrower portion of the projection 9 and has its inner edge 13 beveled off and finished to fit accurately against the valve seat 10 which it overlaps. The upper end 60 of the plunger stem 11 is provided with a knob or enlarged head 14. Surrounding the projecting portion of said stem is a helical spring 15 which bears at one end against the cap and at its other end against the knob or 65 enlarged head at the outer end of the plunger, whereby said spring normally holds the valve 13 up against the seat 10. In this position, the inner enlargement of the plunger is preferably a slight distance above the acid 70 bottle. It is preferable to have the outer surfaces of the enlarged head 12 and of the enlarged portion of the projection 9 flush with each other so as to avoid any danger of particles of glass or of the chemicals lodging 75 at or near their line of contact.

The general operation of my device is similar to that of other chemical fire extinguishers. In order to break the acid bottle, the tank is inverted and dropped, so that the 80 impact of the knob 14 against the ground will force the plunger inwardly. On account of the enlarged head 12 overlapping the valve seat and on account of its never entirely uncovering the projection 9, there is 85 slight probability of any particles of glass lodging against or adhering to the valve seat. This is particularly true when the valve seat is located some distance inwardly from the body of the closure cap. Besides, 90 on account of the beveling of the valve seat and of the undercut edge portion 13, there is a tendency for such portion to scrape off of the valve seat any fragments or foreign matter that may have lodged thereon. As soon as 95 the spring 15 is free to act, it immediately seats the enlarged head against the valve seat 10. In consequence of this arrangement, the bore of the closure cap is as tightly sealed as if a stuffing-box was used, while 100 there is very slight friction and little danger of corrosion. It is noted also that the pressure inside of said tank has a tendency to hold said plunger firmly against said valve seat.

105 Obviously, my device admits of considerable modification without departing from my invention, and I do not wish to be re-

stricted to the construction hereinbefore described.

What I claim is:

1. A tank, a closure cap therefor having an opening therethrough and an exteriorly beveled valve seat surrounding said opening, and a plunger fitting in said opening and having its lower end enlarged and provided with an annular flange interiorly beveled to fit against said valve seat.
2. A fire extinguisher comprising a tank, a closure cap therefor having an opening therethrough and an exteriorly beveled valve seat surrounding said opening, and a plunger fitting in said opening and having its lower end enlarged and provided with an annular flange interiorly beveled to fit against said valve seat and a spring tending to keep said plunger in its outermost position.
3. A fire extinguisher comprising a tank, a closure cap therefor having an opening therethrough and an exteriorly beveled valve seat surrounding said opening, and a plunger fitting in said opening and having its lower end enlarged and provided with an annular flange interiorly threaded to fit against said valve seat, and a spring tending to keep said plunger in its outermost position, said plunger comprising a stem adapted to slide in said opening and having at its lower end an enlargement whose upper shoulder is formed to fit against said valve seat.
4. A fire extinguisher comprising a tank, a closure cap therefor having an opening therethrough and an exteriorly beveled valve

seat surrounding said opening, and a spring-actuated plunger fitting in said opening and having enlargements at its ends, the lower enlargement having an annular flange which is interiorly beveled to constitute a valve for said valve seat and the upper enlargement constituting a knob and serving as an abutment for said spring.

5. A fire extinguisher comprising a tank, a closure cap therefor having an opening therethrough and an exteriorly beveled valve seat surrounding said opening, a plunger fitting in said opening and having an enlargement at its lower end, which enlargement is provided with an annular flange interiorly beveled to fit against said valve seat, and a coiled spring surrounding the projecting portion of the plunger and bearing against a shoulder thereon and against said cap. 55

6. A fire extinguisher comprising a tank, a closure cap therefor having a tubular projection on its inner face, the upper portion of said projection being enlarged and beveled to form a valve seat, a plunger having a stem extending through said tubular portion and having an annular enlargement whose inner edge is beveled to fit against said valve seat.

In testimony whereof I have hereunto signed my name in the presence of two subscribers this 18th day of July, 1906, at St. Louis, Missouri.

JESSE I. HARDY.
